DIVIDED LAST

Filed July 27, 1922

FIG. 1.

FIG. 2.

FIG. 3.

Inventor:
Otto A. Peterson

By *Ellis Scoville*
Attorney.

UNITED STATES PATENT OFFICE.

OTTO A. PETERSON, OF STOUGHTON, MASSACHUSETTS.

DIVIDED LAST.

Application filed July 27, 1922. Serial No. 577,915.

To all whom it may concern:

Be it known that I, OTTO A. PETERSON, a citizen of the United States, residing at Stoughton, county of Norfolk, Commonwealth of Massachusetts, have invented certain new and useful Improvements in Divided Lasts, of which the following is a specification.

My present invention relates to certain developments in lasts particularly two part lasts having a central bearing joint. These lasts are usually pivotally connected at this joint or bearing so that the parts can turn relatively on each other and so that the last can be collapsed for removal from the shoe.

These lasts are usually formed in the upper part of their central division with what is usually termed a V-shaped cut leaving secant faces. These faces are separated when the last is extended, but approach or contact when the last is collapsed. It is desired to maintain the last in extended position with an excess of resistance and also it is desirable that when the last is collapsed it be at least lightly held against free motion.

In my present invention I provide for these features by a simple construction which I have shown in the accompanying drawings and which will be more fully explained in the specification as follows. Throughout the specification and drawings like reference characters are employed to indicate corresponding parts, and in the drawings:

Fig. 1 is a partly sectioned side elevation of a last in extended position.

Fig. 2 a similar view of the last in collapsed position, and

Fig. 3 a plan view looking down on the top of the last.

In the drawings I have illustrated at 1 a fore part and at 2 a heel part linked together on a center pin 5 by a link 6 which is also pinned to the heel part as at 7. The secant face of the heel part is indicated at 3 and that of the fore part 1 is indicated at 4 see Fig. 1. In the last shown the fore part is provided with a cylindrical knuckle member 8 and the rear part with a corresponding concavity 9 which bear on each other. In the upper part of the cylindricity 8 and extending forwardly into the fore part is a bore in which is posi-

tioned a plug 10 which may be of any suitable material. The plug 10 is normally held extended as shown in Fig. 1 by a spring 11.

The bore in the fore part is so disposed with reference to the secant face 3 as to have the plug 10 lie with its rounded end 10¹ slightly over-riding the secant face at the opposite end when the last is extended. This tends to lock the heel part 2 firmly in extended position and to resist any collapsing motion. When it is desired to collapse the last the plug 10 is slightly retracted to clear the edge of the secant face 3 whereupon the concaved surface 9 of the heel part rides over the plug forcing it back. When the heel part is on the way to its upper position as shown in Fig. 2, the end 10¹ of the plug will be slightly under the upper edge of the concavity 9 and thus tend to keep the heel part in elevated position.

The plug 10 is preferably set slightly to one side of the central line of the last and the link 6 preferably works in aligned kerfs in the fore part and heel part. The link may be of any desired shape but conveniently may be my usual arched resilient link of my previous Letters Patent No. 1,195,266.

Various modifications may be made in the details of structure and design all without departing from the spirit of my invention if within the limits of the appended claims.

What I therefore claim and desire to secure by Letters Patent is:—

1. In a divided last, a fore part and a heel part having a central knuckle joint comprising a convex member on one part and a concave member on the other part, a spring pressed follower having a rounded head disposed in a longitudinal bore in the convex part adjacent its intersection with the secant face and adapted to project against the opposite secant face of the cut of the other part when the last is in extended position and engageable with the concave of the other part of the knuckle when the last is in collapsed position.

2. In a divided last, a fore part and a heel part having a central knuckle joint comprising a convex member on one part and a concave member on the other part, a pivotal connecting link uniting the two parts and having one end pivoted substan-

tially in the knuckle center, the fore part and heel part each having secant faces defining a transverse opening exposing said knuckle, a longitudinal bore intersecting the knuckle in its surface so exposed, a spring pressed follower having a rounded head disposed in said bore on a line for normal contact with the base of the opposite secant face when the last is extended

and for contact with the surface of the 10 concave member when the last is collapsed.

In testimony whereof I affix my signature in presence of two witnesses.

OTTO A. PETERSON.
